ION ACCELERATION SYSTEM

John S. Luce and John A. Martin, Oak Ridge, Tenn., assignors to the United States of America as represented by the United States Atomic Energy Commission

Application July 18, 1956, Serial No. 598,725

7 Claims. (Cl. 250—41.9)

The present invention relates to production of relatively large beams of positive ions, and more especially to a method of and apparatus for forming intense beams of positive ions including an ion source and means to accelerate ions from said source through grid electrodes to a desired region of focus. One form of the apparatus may be incorporated with conventional structure to form an improved embodiment of the isotope separator called the calutron.

The calutron is a device for accomplishing isotope enrichment or mass separation of positive ions by accelerating them through an intense magnetic field between a source and a collector. In the calutron, a solid sample material is vaporized by heating, the vapor is ionized by electron bombardment inside an ion source which is maintained at a high positive potential, ions are pulled out of the source by a highly negative accelerating electrode disposed adjacent the mouth of the source, the ions passing through the accelerating electrode are decelerated by causing them to pass through a second grounded electrode, and the resulting beam of ions is passed through the intense magnetic field to the collector. A complete description of a suitable embodiment of the calutron is contained in U.S. Patent 2,709,222, issued to E. O. Lawrence on May 24, 1955.

One primary difficulty in obtaining large ion beams in the calutron is that the maximum current which can be accelerated out of the source is limited by space charge considerations in the accelerating region. To obtain even normal currents, very high accelerating voltages, strong magnetic fields, and large apparatus is required. The amount of current that can be passed through the accelerating electrodes is limited by "blow up" of the ion beam in the acceleration region, resulting from the coulomb repulsion accompanying large beams of charged particles. The observed calutron performance is in accord with theory, since application of Child's 3/2-power law indicates that no more than about 40 ma./in.² of emission could be expected to pass through a focal point. In prior calutron operation, a positive-ion sheath forms between the arc plasma and the accelerating electrodes, the boundary between the arc plasma and the sheath being known as the center of the meniscus. The meniscus is pushed back toward the arc plasma, away from the source grid by the accelerating field which extends into the ion exit slit region and presents a concave surface toward the arc plasma, so that all ions leaving the meniscus normal to the surface thereof must pass through the narrow ion exit slit in the source and a small focal region in the vicinity of the accelerating electrode. The focussing effect of the "dimple" in the arc plasma as caused by the meniscus being pushed back as discussed above results in excellent separation factors for different isotopes collected at the 180° position.

In prior calutron studies, a region of ionization due to oscillatory electrons was noticed in the accelerating electrode slit which caused the ion beam to pass through a focal point in the accelerating electrode slit and this

2

point is termed the "saddle point." It was believed that positive electric fields penetrated the negative accelerating slit, and accordingly a flat grid was placed in the accelerating slit to straighten the positive fields. As a result, the focal region was moved to the grid openings and the beam diverged badly, so that unsatisfactory focusing of the beams on the collectors resulted. Other studies suggested that the beam might be focused if the arc plasma were bowed convex, rather than concave, as if a "virtual focus" point existed behind the arc, but such focussing was never achieved. Widely divergent beams resulted from operation with a single focussing electrode, because the electric field was so weak in the center that the arc bowed toward the accelerating electrode. With such divergent beams, increasing arc current or voltage only increased the numbers of ions draining to the electrode.

With a knowledge of the shortcomings of the known methods and apparatus for obtaining well-focused, intense ion beams, applicants have, as a primary object of 20 their invention, provision of a method of and means for obtaining a relatively intense, well-focused ion beam. Another object of the invention is to stabilize the arc plasma in an ion source while simultaneously withdrawing an ion current of relatively high intensity therefrom. A further object of the invention is to provide a generator of 25 positive ions including an ion source provided with a grid-like ion exit aperture forming a plurality of small, discrete beams, and an accelerating grid disposed closely adjacent the source to further focus and define the discrete beams. Another object is to provide a well-focused intense beam of ions with a single accelerating electrode and a single voltage source. Yet another object of the invention is to provide means for obtaining large ion beam by means of an ion source and an accelerating grid 30 structure which has a small convex curvature to obtain greatly improved focusing of the ion beam at the collector. The major object of the invention is to eliminate the disadvantages inherent in ion beam generators having a narrow focal region in front of the source by providing 35 novel means for withdrawing the beam from the ion source and for focusing it in such a manner that all the ions no longer must pass through any small focal regions.

These objects are attained by providing a series of 40 small apertures in the front face of the ion source, rather than the one continuous ion exit slit, and a single corresponding grid spaced very closely adjacent the ion source to replace both the prior accelerating and decelerating electrodes. With the source at a positive potential, the accelerating grid may be grounded. With such arrangement, intense normally-emergent ion beams may be 45 produced from the source and focussed at a desired location without first passing through a common focal point, so that no beam "blow up" occurs due to coulomb repulsion. One or more of the grids may be convex relative 50 to the front face of the ion source, to improve the focus of the beam at the desired location. By providing a grid across the ion-exit slit, the arc is strengthened in the center and shielded from external fields, so that relatively 55 large currents may be obtained with relatively low accelerating potentials. Preferably, the accelerating grid is curved to improve the focus, while the source grid is flat, tending to push back the center of the arc and thereby preserve the focus.

60 Means by which the above objects may be attained are illustrated in the appended drawings, wherein: Figure 1 illustrates schematically one form of my improved focal system;

65 Figure 2 illustrates a sectional view of one embodiment of the focal system according to the present invention;

3

Figure 3 illustrates a partial plan view of one form of an accelerating grid;

Figure 4 illustrates a partial plan view of one form of a corresponding source grid;

Figure 5 illustrates a preferred embodiment of the grid focal system as it is utilized for isotope separation.

Figure 6 illustrates a partial plan view of the accelerating grid of Fig. 5;

Figure 7 illustrates a partial plan view of the source grid of Figure 5, and

Figure 8 shows schematically a flat-grid source used to inject ions into a system.

Referring now to Fig. 2, a first grid focal system is shown incorporated in a conventional calutron ion source box, including a rectangular graphite box 20 defining an arc chamber 21 therewithin. One wall 22 of the box is provided with a defining slot 24 through which electrons are accelerated from a filament mounted adjacent the wall 22, across the arc chamber, through an aperture 25, to an anode mounted externally of the wall 23. A suitable source box is shown in my prior Patent No. 2,700,107, issued January 18, 1955. A potential of 50-300 volts between box 20 and the filament may be provided to accelerate electrons into the chamber. A vapor-entry slot in the bottom of the box receives vapor as described in the patents cited above. Electrode 26 bridges the vapor exit slit in the top wall of the box, and may be provided with a plurality of aligned small apertures 29 as shown in the plan view, Figure 4. The source grid 26 may be a separate grid structure placed in a corresponding aperture in the top wall of the box 20, as shown in Fig. 2, or it may be a separate plate as shown in Fig. 4, provided with a grid like portion and also a portion without apertures, such that it may be fastened to the top face of the box 20 by some suitable means such as screws. A similar accelerating grid 27 is disposed closely adjacent and in alignment with grid 26.

Referring now to Fig. 3, the accelerating grid 27 may comprise a graphite plate drilled with a plurality of rows of small apertures 28 corresponding to the apertures in the source grid 26. The grid 27 is disposed closely adjacent the grid 26 and in alignment therewith, preferably by mounting the grid plate 27 to the source frame which holds the box 20, through a suitable insulator. The spacing between grids is made very small, but may vary from about $\frac{1}{32}$ " to $\frac{3}{32}$ " going from mass 1 to mass 235. One satisfactory source comprised a grid 27, $\frac{3}{16}$ " thick at its outer edges, and tapering to $\frac{1}{8}$ " thick in the center, grid-like portion, with a grid 26 only $\frac{1}{32}$ " in thickness. In one suitable arrangement, the apertures in the source grid were $\frac{1}{16}$ " x $3\frac{3}{164}$ ", while the slots were $\frac{1}{16}$ " apart along the line of their shortest dimension and $\frac{3}{32}$ " apart along the line of their longest dimension. Corresponding apertures in the accelerating grid were $\frac{1}{16}$ " x $3\frac{7}{164}$ ", and the apertures were spaced $\frac{1}{16}$ " apart along the line of their shortest dimension and $\frac{1}{32}$ " apart along the line of their longest dimension. From the above exemplary dimensions it may be noted that the apertures in the grid 26 are slightly shorter than those of the grid 27, and that the walls between the apertures in grid 27 are correspondingly thinner to allow for alignment of apertures in the two grids.

Referring now to Figure 1, an improved embodiment of the grid focusing system is illustrated schematically. Rectangular graphite box 1 defines an arc chamber 2 in which is established an arc plasma 3 comprising positive ions and electrons. A flat source grid 4 forms the front wall of the arc chamber and is provided with a plurality of apertures to divide the ion beam into a plurality of discrete, small beams. The grid is maintained at the same potential as the arc chamber box 1. Spaced closely adjacent the grid 4 is an accelerating grid 5, the central grid portion of which is slightly convex in curvature. A negative accelerating potential is applied between the grid 5 and the box 1 to form an ion beam and to accelerate it into the analyzing field along the paths illustrated into a

4

focus along the focal line 6, where a collector may be positioned. It will be noted that the focal line is no longer 180° from the arc chamber or from the accelerating region as it is in the normal calutron operation. Rather the curvature of the accelerating grid causes ions of like mass-to-charge ratio to be focused at a point less than 180° from the accelerating region, as shown. This focusing arrangement may be better understood by considering that a virtual focus is formed at a point behind the arc chamber box 1 along the line 7, displaced 180° from the focal line 6. It may be seen that by virtue of this novel apparatus, the actual ion beam never goes through a real focal point until it reaches the collector, so that there is not now a space-charge imposed limitation on the amount or current density of the beam going through a "saddle" point.

Figure 5 illustrates schematically how large ion currents are withdrawn from the arc plasma, accelerated into an analyzing field, separated into discrete beams of ions having different mass-to-charge ratios, and collected in suitable collector pockets. The substance to be separated may be vaporized in any conventional calutron furnace, such as that shown in the Lawrence patent, supra, and allowed to enter an especially constructed, one-piece graphite source box 31 through vapor entry slit 32 in graphite plate 33 which defines the rear of the arc chamber 34. Rather than being provided with the conventional ion exit slit in the forward wall, source box 31 is provided with a slightly convex grid portion having a plurality of small, parallel slots therein. Figure 6 illustrates the front view of the source box 31 looking into the grid portion. The slots 35 are drilled into the slightly convex portion 36, which may be machined in the same block of graphite forming box 31. The electron collimating slits, allowing entrance of the electron beam from the filament and exit of the electron beam to the anode are placed in line with the inner edge of the grid portion as indicated by the slot-shaped arc plasma 37, so that the arc will be formed adjacent the grid portion, and just behind the slit 35.

The accelerating grid 38 may also be a unitary graphite structure in which is machined a grid portion 39 which is slightly concave in the direction facing the convex grid 36. A front view of grid 38, looking into the grid from the left in Fig. 5, is shown in Fig. 7. A plurality of parallel, aligned slots 40 are provided in the curved portion 39 of the grid, the front portion of the member 38 adjacent the slits being cut away to form a recess 41 to allow ample clearance for the ion beam. The grid 38 may be held in place adjacent source 31 through an insulating spacer member fastened to the same frame as is the source, or it may be held in place by a separate support or any other suitable means.

It has been found that the arc plasma is stabilized by the curved grid 36 and that large quantities of ions may be withdrawn from the plasma, since there is no focal point in the accelerating region to limit the numbers of ions which may pass therethrough. Ions may be collected in suitable collector boxes 42 provided with pockets 43, 44 for receiving ions of different masses. It is to be noted that the collector 42 is disposed forward of the source 31 rather than directly above it, as is usually the case because of the virtual focus method of operation achieved by the described curved grid system. With the system illustrated, a broad, intense beam originates at the ion source and narrows to a focus only when it arrives at the collector. Relatively low accelerating potentials are required for the accelerating electrode.

In a preferred embodiment of the apparatus of Figure 5 adapted for separation of isotopes having respective mass to charge ratios of 7 and 6, collection has been achieved with a separation of $1\frac{1}{4}$ inches at the collector, the collector being $3\frac{3}{16}$ inches forward of the source box. With accelerating voltages of 22.5 kilovolts, and a magnetic field of 3100 gauss, collection is readily achieved,

although it will be apparent that other suitable field intensities and accelerating voltages may be provided.

By way of further illustration, the slits 35 may be $\frac{3}{4}$ inch in height while the slits 40 may be $\frac{1}{8}$ inch in height. Those slits may be $\frac{3}{32}$ inch across and separated by spacer members $\frac{1}{16}$ inch wide. The outward edges of the bars between the slits are preferably beveled at 45° , the bars being $\frac{1}{16}$ inch in thickness and the bevel extending approximately $\frac{1}{2}$ of this thickness. In one embodiment of an ion source used, the grid members were $16\frac{1}{2}$ inches in length, with 13 inches between center lines of the first and last of the parallel grids. The grids in the cut-away portion of member 38 may be $\frac{1}{8}$ inch in thickness, or twice the thickness of the grid spacer members in the source 31. While considerably larger total ion currents can be consistently received, it has been found that the beam focus is sufficiently sharp to assure acceptable isotopic enrichment at total currents of around 700 milliamperes with uranium. Beam currents of about 5 amperes of H^+ ions have been received. By providing vertical, rather than horizontal grids, beam dispersion vertically is about $\pm 2\%$, rather than $\pm 7\%$, allowing 180° isotope separation.

In the preferred embodiment shown the source grid outer surface is machined to a 4 inch radius, the outer surface of the accelerating grid is machined to a $4\frac{1}{4}$ inch radius, and the inner surface of the accelerating grid is machined to a $4\frac{1}{16}$ inch radius. The cutaway portion of the accelerating grid is $1\frac{1}{8}$ inches at its outermost point.

It has been found that replacing the high potential accelerating electrode of the calutron by the present grid, closely adjacent the arc and maintained at the same potential as the arc chamber, greatly stabilizes the arc, so that better operation of the entire unit results. It has been further found that with this novel acceleration system the source may be operated at 20 kilovolts rather than at 38 kilovolts as required in standard calutron operation, the accelerating grid may be operated at ground potential, and the high negative potential supply formerly used for the accelerating slit is no longer required. Elimination of the requirement of the high negative voltage thus eliminates a costly power supply and also makes operation more efficient, since the ion drain to the highly negative electrode is eliminated. Reduction in the potential requirements of the accelerating voltage source from 38 to 20 kilovolts achieves a further major cost savings in both original cost and operating expense. Further, as pointed out above, the ratio of power supply drain to the useful ion beam, which forms an index to the cost of operation, is appreciably smaller, that is 1.3-2.5, as compared with 4.5 for a conventional calutron source.

It has further been found that sources of the character described herein are highly useful as sources of large currents of ions for injection into a circulating charged particle system. Since the ions of the beam emerging from the flat grids of the source come to a focus at the 90-degree point, such point is a convenient point of entry for the ions into a circulating system.

As shown in Fig. 8, ions are formed in a source chamber 50 defined by the walls of box 51 by means of an electron beam passing from an external filament to the box wall or to a cathode. The arc discharge 52 so formed is shown in cross-section. A flat source grid 53 is formed by vertical slots in the front face of box 51, corresponding to the grid shown in Fig. 7, except that grid 53 is parallel with the rear wall 54 of box 51. A corresponding flat accelerating grid 55 is provided closely adjacent grid 53 in the same closely-spaced relationship as between the curved grids of Fig. 5. Ions from the source are accelerated by a potential applied between the grids, and are brought to a focus at the 90° point by the applied magnetic field, which is shown by the dot H as coming out of the plane of the paper. The broad

beam 57 emerging from grid 55 is focused onto the utilization device 56 such as an accelerator for charged particles.

Very large useful ion beams may be obtained, since the effects of reduced spacing and high voltage gradients and the novel geometry of the system overcome the space charge limitation of the calutron focal region, so that beams orders of magnitude greater may be produced and focused. The long dimension of the grids may be either vertical or horizontal, that is, normal or parallel to the magnetic field. It has been found that better focused beams may be obtained, for purposes such as isotope separation, by using vertical grids. The individual ion beams emerging from the slits appear to repel each other so as to reduce divergence parallel to the magnetic field, providing a narrower, more uniform beam than can be obtained by horizontal grids, where there is not that unifying effect bunching the beams together.

It may be seen that the novel means for generating ions herein described may be applied in various ways to different problems such as injection of ions into accelerators, isotope separations, and the like. Other applications where intense beams of singly and multiply charged ions will be apparent to those skilled in the art. It is, therefore, intended that the scope of the invention not be limited to the physical embodiments described, but only by the attached claims.

Having described the invention what is claimed as novel is:

- 30 1. In isotope separation equipment comprising an ion source having an ion exit passage, an ion collector, means for providing a strong magnetic field between said source and collector, and a source of potential for accelerating ions from said ion source to said collector through said field, the improvement comprising a first multi-apertured plane member forming a grid disposed across said exit aperture and contacting the walls of said source, a second multi-apertured convex member forming a focussing grid disposed in spaced relation to said first grid between said source and collector, said grid apertures having their longest dimension normal to the direction of said magnetic field, and means connecting said source of accelerating potential between said first and said second grids.
- 35 2. In isotope separating means provided with an arc chamber, a source of ions, means for establishing an arc within said chamber, one wall of said chamber being provided with an aperture for the escape of ions, an ion collector disposed in spaced relationships from said source, and means for establishing a strong magnetic field between said collector and said chamber, the improvement comprising a first plane grid member disposed across said aperture and contacting the walls of said chamber, a convex grid member disposed adjacent said plane grid member between said chamber and said collector, said grids having openings the longest dimensions of which are normal to the direction of said magnetic field, and a source of potential coupled to said chamber and convex grid to accelerate ions to said collector, the radius of curvature of said convex grid member, the potential established by said source, and the strength of said magnetic field being so related that ions of a selected mass from said chamber pass through said grids and come to a focus upon said collector.
- 40 3. In ion generating means of the character described including an ion source provided with an ion exit aperture, an ion collector, and means for establishing a magnetic field between said source and said collector, the improvement comprising a first convex grid member disposed across said ion exit aperture, a second convex grid member disposed adjacent said first grid member and aligned between said first grid and said collector, said grid members having openings the longest dimensions of which are normal to the direction of said magnetic field, both of said grid members having radii of curvatures operative to focus ions of selected masses from said

- 75

source upon said collector, and means coupled between said grids for accelerating positive ions from said source through said grids to said collector.

4. In an ion producer comprising means defining an arc chamber having an ion exit aperture, means for establishing an arc therethrough, means for feeding vapor into said arc, an ion receiving means disposed in spaced relationship to said chamber, means for establishing a strong magnetic field encompassing said chamber and receiving means, the improvement comprising: means for stabilizing said arc within said chamber, said means comprising a first multi-apertured grid member disposed across said ion exit aperture and contacting said arc; means for accelerating ions from said arc through said field to said ions receiving means comprising a second multi-apertured convex grid member disposed closely adjacent said first grid and aligned with the apertures therein; and a source of potential having a positive terminal connected to said arc chamber and a negative terminal connected to said second grid to accelerate positive ions from said chamber through said grid to said collector, at least said second grid having a radius of curvature such that ions of a selected mass from said source passing therethrough will be focused upon said collector, said grid apertures having their longest dimension normal to said magnetic field and to the direction of ion travel therethrough.

5. In isotope separating means provided with a source of gas to be ionized, said gas including at least two isotopes to be separated, an evacuated tank, means for establishing a magnetic field in said tank, and electron beam means for ionizing said gas within a chamber, the improvement comprising a back plate having a central aperture for receiving gas from said source; an elongated graphite block provided with a generally U-shaped cavity defining an ionization chamber and having a back surface contacting said back plate to receive gas therethrough, the ends of said block being provided with curved slits conforming to the bottom of said cavity to allow passage of said electron beam therethrough, the bottom of said cavity and front surface of said block being correspondingly arcuate and convex and provided with a plurality of spaced slits; and an accelerating electrode provided with a corresponding arcuate, convex apertured portion disposed closely adjacent said front surface of said block, a plurality of collectors, means connected to said front surface and accelerating electrode for accelerating ions

from said electron beam through said field to said collector, said collectors being disposed forward of said ionization chamber at substantially 180° from the virtual focal point defined by said arcuate surfaces and said front surface slits and electrode apertures having their longest dimension normal to the direction of said magnetic field.

6. In a source of ions for particle accelerators and the like, provided with a source box defining an ionization chamber, means for admitting vapor to be ionized to said chamber, and means for establishing an arc discharge across said chamber, the improvement comprising: means for establishing a magnetic field parallel to said arc, means to receive said ions disposed in said field in spaced relation to said box, a first planar ion exit grid electrode provided with a plurality of parallel apertures, a second planar grid electrode provided with corresponding apertures aligned with said first grid apertures disposed adjacent said first grid, and means for establishing an electrical field between said electrodes to accelerate ions from said arc, said apertures being aligned normal to the direction of said field and to a line drawn between said electrodes.

7. In an ion producer operating in a magnetic field and comprising an arc chamber provided with an ion exit aperture in one wall and means for establishing an arc discharge adjacent said wall and parallel to said wall and said magnetic field to produce ions, the improvement comprising a first multi-apertured grid disposed within said exit aperture in said wall to shield said arc from external electrical fields, a second multi-apertured grid disposed closely adjacent said first grid and outside said chamber, said apertures of both said grids being elongated with their longest dimension normal to said magnetic field and being aligned to permit ion egress, and a source of accelerating potential connected between said arc chamber and said second grid to accelerate positive ions out of said chamber.
